DESIGN FOR A PERCOLATOR

Robert Heller, New York, N. Y., assignor to The
A. C. Gilbert Company, New Haven, Conn., a
corporation of Maryland

Application August 4, 1936, Serial No. 64,240

Term of patent 14 years

To all whom it may concern:

Be it known that I, Robert Heller, a citizen of the United States, residing at New York, in the county of New York and State of New York, have invented a new, original, and ornamental Design for a Percolator, of which the following is a specification, reference being had to the accompanying drawing, forming part thereof.

Fig. 1 is a side elevational view of a percolator showing my design; and

Fig. 2 is a top plan view thereof on a reduced scale.

I claim:

The ornamental design for a percolator as shown.

ROBERT HELLER.
